(57) **CLAIM**

The ornamental design for a packaging, as shown and described.

DESCRIPTION

FIG. 1 is a perspective view of a packaging showing my new design according to a first embodiment;

FIG. 2 is a front view of the design shown in FIG. 1;

FIG. 3 is a rear view of the design shown in FIG. 1;

FIG. 4 is a top view of the design shown in FIG. 1, the bottom view being identical thereto;

FIG. 5 is a right side view of the design shown in FIG. 1;

FIG. 6 is a left side view of the design shown in FIG. 1;

FIG. 7 is a sectional view of the design shown in FIG. 1 as viewed between lines 7 and 7' in FIG. 2;

FIG. 8 is a perspective view of a packaging showing my new design according to a second embodiment;

FIG. 9 is a front view of the design shown in FIG. 8;

FIG. 10 is a rear view of the design shown in FIG. 8;

FIG. 11 is a top view of the design shown in FIG. 8, the bottom view being identical thereto;

FIG. 12 is a right side view of the design shown in FIG. 8;

FIG. 13 is a left side view of the design shown in FIG. 8; and, FIG. 14 is a sectional view of the design shown in FIG. 8 as viewed between lines 14 and 14' in FIG. 9.
